GRID STRUCTURE

Warren R. Ferris, South Orange, N. J., assignor to
General Electric Company, a corporation of
New York

Application May 29, 1930, Serial No. 457,128

3 Claims. (Cl. 250—27.5)

The present invention relates to electron discharge apparatus, more particularly to those devices in which the electron stream is intercepted by a plurality of grid members.

The usual form of thermionic amplifier comprises a filament, one or more helical grids surrounding the filament and an anode. There may be used two, three, four or more grids depending on the tube characteristics desired and the amount of electrostatic control necessary, and for other reasons. The grid arrangement generally includes a member called a control grid whose sole function is to offer a variable control of the electron stream and another electrode termed a screen grid which serves to reduce or neutralize the electrostatic capacity normally existing between the control grid and the anode and to increase the amplification of the tube. The turns of the screen grid which is positioned between the control grid and the anode, are usually wound closer together, i. e. having less pitch and more turns per inch of length, than those of the control grid and it often happens that the ratio of the respective number of turns is two, three or other multiple. Under any of these conditions, a certain number of turns of the outer or screen grid will lie between the adjacent turns of the inner or control grid as viewed from the outside of the tube looking toward the filament, and so be subject to the electron impact of the high velocity electron stream. However, other portions of the screen grid will lie directly in front of the inner grid wires or directly in back of each control grid wire considered from the direction of electron travel, and hence will be shielded to a large extent from electron impact. It has been found that as the screen grid current is increased, for example, by raising the voltage applied thereto, the screen grid becomes heated along those lengths of wire positioned in the unobstructed beam of electrons but is relatively cool at the remaining portions of the grid, along those lengths which are in the electron shadow of the control grid wires. The condition of localized heating produces in the screen grid alternate lengths of heated and unheated portions which may affect the capacity neutralizing function of the member and cause many other defects such as variations in the space current flowing to the anode, fusing and warping of the grid structure, also the liberation of deleterious gases. The condition of unevenness of heating, in addition, may reduce the maximum power output of the tube which ordinarily would be derived from the

use of an additional space charge grid because the greater the density of the electron stream the more pronounced is the localized heating effect.

An object of the present invention is to improve the grid construction and arrangement in thermionic devices to the end that each of the grid members will be heated uniformly throughout its length. This object is attained, in brief, by reducing that portion of the grid subject to the direct impact of the high velocity electron stream and to allow the grids to shield one another in the greatest possible degree without sacrificing the efficiency of the tube. According to my invention, the improved arrangement consists in winding the successive grids in opposite directions so that the differences in pitches of the respective grid members become additive and the shortest length of each grid is presented to the direct action of the electron stream.

The invention will be better understood when reference is made to the following description and the accompanying drawing in which Fig. 1 represents an elevational view partly in section of a tube improved in accordance with my invention; Fig. 2 is a plan view looking down on the electrode structure; Fig. 3 shows the relation between a pair of grids and the filament; Fig. 4 is a diagrammatic view depicting in rather an exaggerated form by way of comparison the prior art method of arranging the screen grid and control grid wires in the righthand view, and on the left, the technique as improved in accordance with my invention is illustrated; Fig. 5 is a view useful in explaining the invention, and showing typical electron paths which intercept the grids, while Fig. 6 is a diagrammatic view of a pentode in which my invention finds application, also associated circuits.

Referring to Fig. 1, numeral 1 designates an evacuated envelope of the tipless type so-called, terminating in a combined re-entrant stem and press 2 and containing a plurality of electrodes. The electrode organization includes an M shaped filament 3 supported at the bottom by three stiff wires 4, the two outer of which serve as leading-in conductors. The upper apexes of the filament are supported in the usual manner by means of two uprights 5 which are secured in a bead of glass (not shown) and supported from the stem 2. Arranged symmetrically about the filament, there are three grids 6, 7, 8, also an anode 9, as shown more clearly in Fig. 2, the innermost grid 6 functioning as the electrostatic control member, the intermediate grid 7 as the

screen member and the outermost grid 8 serving to reduce or suppress the secondary emission from the anode. Each grid is supported between respective pairs of vertical rods 10 secured in the 5 press 2, one rod per grid except in the case of the outermost grid being extended through the stem to constitute a leading-in conductor. These conductors, in addition to the filament leading-in wires, may be connected to a plurality of contact pins 11, molded in a base 12. The upper ends of the grid rods are held in position by a mica disc or plate 13 bridged between the rods 14 which are secured in the press 2. The anode or plate member 9 takes on a rectangular shape and 10 is provided with rectilinear extensions 15 which embrace the rods 14. The outermost grid or secondary emission suppression member 8 is conveniently formed as a coarse mesh preferably of nickel, while the inner grids 6 and 7 are wound 15 as flat helixes in order to accommodate their form to the M shaped filament. The control grid 6 is preferably made of nichrome and the screen grid of molybdenum. The present invention is directed more especially to the manner of winding the inner grids 6 and 7, as will be explained hereinafter although it will be understood that the principles of my invention apply equally well 20 to any pair of wound grids in an electrode organization.

30 Fig. 6 shows in diagram a typical circuit in which the improved tube finds application. In this figure, numeral 16 designates an input transformer connected between the control grid 6 and filament 3. The plate battery or other source 35 of electromotive force 17 serves to energize the plate circuit and the screen grid circuit in parallel while the secondary emission suppression grid 8 is connected effectively to the mid-point of the filament as indicated by reference character 19a, 40 for well understood reasons; this connection is conveniently made within the tube. The output current of the transformer may flow through transformer 18 to a load circuit. The control grid circuit is generally provided with a negative 45 bias battery 19.

50 From the circuit diagram, it is evident that a relatively high potential is applied to the screen grid 7 under operating conditions and it has been found that when the turns on the latter greatly exceed those on the control grid, and in an extreme case bear a multiple or a near multiple relation therewith, certain lengths of the screen grid wires are excessively heated during operation. The reasons for this effect will be clear 55 from an inspection of Fig. 5 which indicates the electrostatic fields surrounding the electrodes. In this figure, the filament 3 is shown as emitting electrons which move toward the plate 9 under the potential gradient established by the 60 plate battery, which electrons are intercepted by the control grid 6 and the screen grid. The wires 6 are surrounded by a negative electrostatic field indicated roughly by the dot and dash lines *a* which repel the electrons shown as dotted lines *b* and converge the same into a highly concentrated mass sweeping through the space between the wires 6. The greatest density of the electron stream occurs mid-way between the wires. It is apparent that those portions *1b* of the screen 65 grid which are in the direct path of the electrons, and particularly in the path mid-way between the wires 6, will be subject to greater electron impact than screen grid wires *1c* which are in line with the control grid wires, hence shielded 70

by the latter. In this figure the secondary emission suppression grid has been omitted for the sake of clearness although it will be understood that such a grid may be employed in combination with the other grids and may also be improved in accordance with the principles of my invention. 5

In order to minimize the heating effects of the wires which are exposed to the full impact of the electron beam, it is apparent that only such wire as is absolutely necessary should be presented to 10 the electrons. In accordance with my invention, this end is accomplished by winding the screen grid helix in a direction opposite to that of the control grid, as indicated in the lefthand view of Fig. 4. This manner of winding serves effectively to add the pitches of the helixes as measured from a common datum line and to increase the angle at the point of intersection between the wires so that the length of each screen grid wire positioned between the turns of the control grid 15 is reduced to the minimum. When the wires are wound in the same direction, according to the prior art, the pitches, as measured from the common datum line, are subtractive and the angle between intersecting wires is very acute. The 20 advantage of winding the grids in opposite directions is readily appreciated from the comparison of the two views, in Fig. 4. In the prior art arrangement, at the right, the wires *1b* of the screen grid are exposed over their entire length 30 between the support rods 10 to the full impact of the electron stream and hence will seriously heat, while the adjacent wires *1c* are for the most part shielded by the control grid wire 6 and will not heat to any appreciable extent. However, when 35 the wires cross in opposite directions, as indicated in the lefthand view, the effective length of screen grid wire in the space between the turns of the control grid is materially shortened and the heating effect reduced in like degree. Thus, in the 40 improved construction, the length of wire *1b* which diagonally spans each pair of control wires 45 6 is much less than the distance between the inner support rods 10 hence less than the length of screen grid wire of the prior art arrangement which would normally be exposed to the full impact of the electrons. It will also be noted that the wires *1c*, which in the prior art construction were completely shielded by the control grid, are 50 now exposed to the electrons in substantially the same amount as the wires *1b*, hence subjected to substantially the same heating effect. 55

While my invention has been explained with particular reference to a pair of grids having turns in a one-to-two relation it is evident that the improvement applies to all turn ratios and more especially to those cases in which the number of turns on the screen grid is slightly less or greater than a multiple of the number on the control grid. In one type of tube improved in accordance with my invention the control grid had 15 turns per inch and the screen grid 34 turns per inch and it was found that the screen grid was heated uniformly over its entire length. 60 On the other hand, when the grids were wound in the same direction according to the teachings of the prior art, the wire became heated in lengths approximately $1/3$ " apart. 65

The advantages offered by my invention are 70 secured without detracting in any substantial degree from the control exercised by the various grid members and therefore do not affect the electrical characteristics of the tube. 75

What I claim as new and desire to secure by Letters Patent of the United States is:

1. An electron discharge device comprising a cathode, an anode, a plurality of helically wound grids positioned therebetween, a pair of said grids being wound on the same axis and in opposite directions.

2. In an electron discharge device, the combination of a grid comprising a wire wound in a plurality of turns in one direction, and an addi-

tional grid comprising a wire wound in a plurality of turns in the opposite direction.

3. In an electron discharge device, the combination of two grids each comprising a wire wound in a plurality of turns in one direction, and an additional grid between the two first mentioned grids comprising a wire wound in a plurality of turns in the opposite direction.
